United States Patent Office

Des. 175,192
Patented July 19, 1955

175,192

CURTAIN FABRIC OR SIMILAR ARTICLE

Max Sadinoff, New York, N. Y.

Application June 4, 1954, Serial No. 30,816

Term of patent 3½ years

(Cl. D47—6)

The figure is a plan view of a curtain fabric showing my new design.

I claim:

The ornamental design for a curtain fabric or similar article, as shown.
